UNITED STATES PATENT OFFICE.

ERNEST JAMES SMITH, OF CHICAGO, ILLINOIS, ASSIGNOR TO THE GOSS PRINTING PRESS COMPANY, OF CHICAGO, ILLINOIS, A CORPORATION OF ILLINOIS.

INK-TRANSFERRING MECHANISM.

1,262,709.

Specification of Letters Patent. Patented Apr. 16, 1918.

Application filed June 19, 1916. Serial No. 104,466.

To all whom it may concern:

Be it known that I, ERNEST JAMES SMITH, a subject of the King of England, and a resident of Chicago, in the county of Cook, 5 State of Illinois, have invented certain new and useful Improvements in Ink-Transferring Mechanisms, of which the following is a specification, reference being had to the accompanying drawing.

10 My invention relates to ink transferring mechanisms for printing presses, comprising one or more oscillating rollers, and it has for one of its objects the provision of a new and improved form and arrangement of 15 parts by reason of which such a mechanism can be operated at an effectively high speed without undue wear and strain upon the parts. To this end I have provided an oscillating roller mechanism comprising two 20 rollers one upon each side of the line of centers between the fountain-roller or other ink applying device and the ink cylinder, the two oscillating rollers being connected to swing together by a single operating mechanism. It is one of the objects of my invention 25 to provide means for controlling the timing of the rollers whereby the time of rest between operative movements of the rollers or the period otherwise occupied between successive engagements with the fountain-roller and the inking cylinder may be 30 varied relative to the period during which each roller in turn is in operative engagement. It is another object of my invention 35 to improve devices of this type in sundry details hereinafter pointed out. The preferred means by which I have accomplished my several objects are illustrated in the drawings and are hereinafter specifically 40 described. That which I believe to be new and desire to cover by this application is set forth in the claims.

In the drawings:

Figure 1 is a diagrammatic view showing 45 a part of a press embodying my improved inking arrangements;

Fig. 2 is a cross-section taken on line 2—2 of Fig. 1; and

Fig. 3 is a cross-section taken on line 3—3 50 of Fig. 1.

Referring to the several figures of the drawings in which corresponding parts are indicated by the same reference characters,

65 10 indicates the framework of a press hav-

ing mounted thereon a form cylinder 11, an inking cylinder 12, form rollers 13—14, and vibrating rollers 15 of any suitable type. An inking roller 16 mounted upon a shaft 17 is adapted to be driven by a worm-gear 60 18 meshing with a worm 19 mounted upon a shaft 20 driven by any suitable mechanism at the desired rate of rotation. Ink is adapted to be delivered upon the cylinder 16 by a nozzle 21 having a supply of ink fed thereto through the pipe 22 from any suitable source. A scraper-blade 23 engages the roller 16, being adapted to be adjusted by any suitable means, as is well understood in the art. An auxiliary scraper 24 held in engagement with the roller 16 through the medium of a spring 25 is employed for scraping any lint and surplus ink from the surface of the roller. A trough 26 receives the surplus ink from the roller 16 from which 70 it is conveyed by a pipe 27 to any suitable point.

A shaft 28 extending between the inking roller 16 and the inking cylinder 12 has fixed thereon near each end a head 29. Revolubly 80 mounted between the heads 29 by means of two shafts 30—31 are two oscillating rollers 32—33, respectively, so positioned relative to each other and relative to the roller 16 and the cylinder 12 that they are capable of oscillating between the roller 16 and the cylinder, one roller 32—33 being always in contact with the cylinder when the other is in contact with the roller 16.

The means for operating the oscillating 90 rollers 32—33 comprises a crank-arm 34 fixed upon the shaft 17, the outer end of the arm 34 being connected by means of a link 35 with an arm 36 revolubly mounted upon the axis of the cylinder 12. Revolubly 95 mounted upon the same axis and movable relative to the arm 36 are two cam members 37—38, being held in adjustable position relative to the arm 36 by means of a screw-threaded pin 39 engaging threaded lugs 100 40—41 upon said cam members, respectively, the pin 39 being held against movement longitudinally of itself relative to the arm 36 by means of a double yoke 42 carried by the arm. As is best shown in Fig. 1, the outer ends of the cam members 37—38 overlap each other, serving to provide a high cam portion 43 upon the cam member 38, an intermediate cam portion 44 at the end of the member 37 and a low cam portion 45 on the 105 member 37 and a low cam portion 45 on the 110

member 37 adjacent to the intermediate portion 44. An arm 46 fixed upon the shaft 28 is adapted to engage the cam members 37 and 38, the engagement being effected in the 5 construction shown through the medium of a roller 47 revolubly mounted upon the free end of the arm 46. A spring 48 tends to hold the arm 46 turned to the limit of its movement in counterclockwise direction in 10 Fig. 1.

Upon the rotation of the shaft 17 through the medium of the worm-gear 18, the arm 36 is reciprocated about its axis carrying with it cam members 37—38. When the 15 arm 36 is moved downward from its highest position, the highest cam portion 43 engages the arm 46 and moves it to the right until the roller 33 engages the roller 16 and the roller 32 engages the cylinder 12, as shown 20 in Fig. 1. This position is maintained also during the first part of the upward movement of said arm 36. When in the downward movement of the arm 36 the roller 47 is brought into contact with the intermediate 25 cam portion 44, the rollers 32—33 are moved a short distance in counterclockwise direction in Fig. 1, serving to hold both rollers out of operative engagement. When the roller 47 passes from the intermediate 30 cam section 44 to the low cam section 45 at the end of the downward stroke of the arm 36, the roller 33 is moved into engagement with the cylinder 12 and the roller 32 is moved into engagement with the roller 35 16. Upon the reverse movement of the arm 36, the roller 32 is moved again out of engagement with the roller 16 and into engagement with the cylinder 12 while the roller 33 is moved out of engagement with 40 the cylinder 12 and again into engagement with the roller 16. Upon each movement of the rollers 32—33, the amount of time during which they are held out of operative engagement depends upon the 45 effective length of the intermediate cam portion 44. By an adjustment of the screw-threaded pin 39, the effective length of the intermediate cam portion 44 can be varied, the screw-threads being such as to move 50 both cam members together toward the arm 36 or together away from the arm. The arrangement and proportions are such that in all adjustments of the cam members 37—38 the effective portion of the intermediate cam portion 44 remains centered 55 relative to the arm 36.

By the use of two oscillating rollers 32—33 adapted to be moved in opposite directions by the actuating mechanism so as 60 to act alternately for applying ink from the roller 16 to the cylinder 12, I am enabled to increase the number of applications of ink to the cylinder within a given time very materially as compared with a construction 65 employing only a single oscillating roller,

this result being attained without an excessive speed of operation of the oscillating means.

What I claim as my invention and desire to secure by Letters Patent, is—

1. In a printing press, the combination of an inking roller, means for supplying ink thereto, an inking cylinder revolubly mounted adjacent thereto, a pair of oscillating rollers adapted to be swung into and out of contact with said inking roller and said cylinder on opposite sides of their line of centers, and means for swinging said oscillating rollers adapted to hold each roller in intermediate position upon each movement 75 in each direction.

2. In a printing press, the combination of an inking roller, means for supplying ink thereto, an inking cylinder revolubly mounted adjacent thereto, a pair of oscillating 85 rollers adapted to be swung into and out of contact with said inking roller and said cylinder on opposite sides of their line of centers, and means for swinging said rollers adapted to stop the oscillating rollers in intermediate position upon each movement in 90 each direction.

3. In a printing press, the combination of an inking device, means for supplying ink thereto, an inking cylinder revolubly 95 mounted adjacent thereto, an oscillating roller adapted to be swung between said first-named two members, and cam means for controlling the position of said roller, comprising a high portion adapted to hold 100 said roller in contact with one of said members, a low portion adapted to hold said roller in contact with the other member, and an intermediate portion adapted to hold the roller out of contact with both of said 105 members.

4. In a printing press, the combination of an inking device, means for supplying ink thereto, an inking cylinder revolubly mounted adjacent thereto, an oscillating roller 110 adapted to be swung between said first-named two members, cam means for controlling the position of said roller,—comprising a high portion adapted to hold said roller in contact with one of said members, a low portion adapted to hold the roller in contact with the other member, and an intermediate portion adapted to hold the roller out of contact with both of said members,—and means for adjusting the effective 115 length of said intermediate cam portion for varying the period during which said oscillating roller is in its intermediate position relative to the time during which it is in operative contact with said members.

5. In a printing press, the combination of an inking device, means for supplying ink thereto, an inking cylinder revolubly mounted adjacent thereto, an oscillating roller adapted to be swung between said 120 125 members.

- inking device and said cylinder, cam means for controlling the position of said roller,—comprising a cam member provided with a high portion adapted to hold said roller 5 swung to the limit of its movement in one direction, and a second cam member provided with a low portion adapted to hold the roller swung to the limit of its movement in the opposite direction and with an intermediate cam portion adapted to hold the roller in an intermediate position,—and means for adjusting one of said cam members relative to the other for varying the effective length of the intermediate portion 10 of said cam.
6. In a printing press, the combination of an inking device, means for supplying ink thereto, an inking cylinder revolvably mounted adjacent thereto, an oscillating roller adapted to be swung between said inking device and said cylinder, cam means for controlling the position of said roller,—comprising a cam member provided with a high portion adapted to hold said roller 15 swung to the limit of its movement in one direction, and a second cam member provided with a low cam portion adapted to hold the roller swung to the limit of its movement in the opposite direction and with an intermediate cam portion adapted to hold the roller in an intermediate position,—means for actuating said cam for swinging said roller, and means for adjusting said cam members relative to said actuating means adapted to vary the effective length 20 of said intermediate cam portion.
7. In a printing press, the combination of an inking device, means for supplying ink thereto, an inking cylinder revolvably mounted adjacent thereto, an oscillating roller adapted to be swung between said inking device and said cylinder, cam means for controlling the position of said roller,—comprising a cam member provided with a high portion adapted to hold said roller swung to the limit of its movement in one direction, and a second cam member provided with a low cam portion adapted to hold the roller swung to the limit of its movement in the opposite direction and with an intermediate cam portion adapted to hold the roller in an intermediate position,—means for actuating said cam for swinging said roller, and means for adjusting said cam members relative to said actuating means adapted to keep said cam members in operative centered position relative to said actuating means and to vary the effective length 25 of the intermediate cam portion.
8. In a printing press, the combination of an inking device, cam means for controlling the position of said roller,—comprising a cam member provided with a high portion adapted to hold said roller swung to the limit of its movement in one direction, and a second cam member provided with a low cam portion adapted to hold said roller swung to the limit of its movement in the opposite direction and with an intermediate cam portion adapted to hold the roller in an intermediate position,—a swingingly-mounted arm, adjustable connections between said cam members and said arm by an adjustment of which the effective length of the intermediate cam portion can be varied, and means for swinging said arm.
9. In a printing press, the combination of an inking roller, means for supplying ink thereto, an inking cylinder revolvably mounted adjacent thereto, a pair of oscillating rollers adapted to be swung into and out of contact with said inking roller and said cylinder on opposite sides of their line of centers, cam means for controlling the position of said rollers,—comprising a swingingly-mounted cam member provided with a high cam portion adapted to hold said rollers swung to the limit of its motion in one direction, and a second swingingly-mounted cam member provided with a low cam portion adapted to hold said rollers 30 swung to the limit of their motion in the opposite direction and with an intermediate cam portion adapted to hold said rollers in an intermediate position,—a swingingly-mounted arm, adjustable connections between said cam members and said arm adapted to adjust said members toward and from each other in centered operative position relative to said arm for varying the effective length of the intermediate cam portion, a crank driven in timed relation to the speed of the first-mentioned inking roller, and connections between said crank and said arm for reciprocating said arm.
10. The combination with an inking cylinder, and an inking roller, of an ink transferring device, comprising a rocking support, rollers carried thereby and movable oppositely by the rocking thereof alternately into engagement with said inking roller and said cylinder respectively, cam means adapted by reciprocatory movement to rock said support, and means operated by the rotation of said inking roller for reciprocating said cam means.

ERNEST JAMES SMITH.
